Primary Examiner — Justin C Dodson*Assistant Examiner* — Eric Eldone Tormanen(74) *Attorney, Agent, or Firm* — Justin Lampel(57) **CLAIM**

The ornamental design for a light therapy lamp, as shown and described.

DESCRIPTION

FIG. 1 is a first perspective view of a light therapy lamp showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is an enlarged view of a portion of FIG. 1.

The dashed lines in the drawings depict portions of the light therapy lamp that form no part of the claimed design. The

(Continued)

dot-dash broken lines depict the bounds of the enlarged views that form no part thereof.
